Patented Apr. 16, 1912.

UNITED STATES PATENT OFFICE.

EUGENE A. GRAVES, OF RUTLAND, VERMONT, ASSIGNOR OF FORTY-FIVE ONE-HUNDREDTHS TO FREDERICK W. SAVAGE, OF GRANVILLE, NEW YORK, AND TEN ONE-HUNDREDTHS TO SAMUEL GENO, OF RUTLAND, VERMONT.

PROPELLING MECHANISM FOR VESSELS.

1,023,515.

Specification of Letters Patent.

Patented Apr. 16, 1912.

Application filed June 22, 1910. Serial No. 568,258.

To all whom it may concern:

Be it known that I, EUGENE A. GRAVES, a citizen of the United States, and resident of Rutland, county of Rutland, State of Vermont, have invented an Improvement in Propelling Mechanism for Vessels, of which the following description, in connection with the accompanying drawing, is a specification, like characters on the drawing representing like parts.

This invention has for its object the production of novel mechanism for propelling steam and other motor-driven vessels whereby the efficiency of the power employed is materially amplified, and, for a given horse-power and hull, the speed of the vessel is greatly increased.

It is well known that there is a great difference between the theoretical and the practical efficiency of the screw propeller as commonly used, for theoretically the pitch of the propeller determines the axial distance traversed during one revolution, but in practice a propeller working in the unconfined water does not travel such theoretical distance by an amount termed the apparent slip. The rotation of the propeller tends to force a portion of the water engaged thereby outward from the axis of rotation, and thus reduces the re-action upon the boat which tends to push it forward.

In my present invention I mount the propeller within a laterally confined body of water co-axial with the propeller and under pressure from the volume of water at one or both ends of the confined body, so that when the propeller is revolved it tends to force such confined body of water in an axial direction from the confining means, but this tendency is resisted by the external volume of water, hence the vessel is driven in the opposite direction. Inasmuch as the confining means prevents any radial movement of the confined body of water in which the propeller works there is a practical elimination of slip, and the axial distance traversed by the propeller in one revolution closely approaches the theoretical distance. Ordinarily the motive power is applied to the propeller at or near its axis of rotation, so that the leverage of the resistance to rotation is practically at its maximum, but in my present invention the mo-

tive power is applied at or near the periphery of the propeller, and by such arrangement I secure highly satisfactory results, not only as to power consumed but as to efficiency and speed.

The various novel features of my invention will be fully described in the subjoined specification and particularly pointed out in the following claims.

Figure 1 is a side elevation of the hull of a vessel equipped with propelling mechanism embodying one form of my invention; Fig. 2 is a horizontal section taken through the hull substantially on the line 2—2, Fig. 1, looking down; Fig. 3 is a transverse section on the line 3—3, Fig. 1, looking toward the left; Fig. 4 is an enlarged longitudinal sectional detail taken through the axis of a propeller and its inclosing tube by means of which the body of water in which the propeller works is confined against lateral movement, the section being taken on line 4—4, Fig. 2.

In the present embodiment of my invention the hull A of the vessel is provided with two tubular containers B, B, located in parallelism with each other and with the keel of the vessel, and extended longitudinally within the hull for the greater part of their length, the open ends of the containers being fixedly secured to the shell or hull near the bow and stern thereof in any suitable manner. As shown in Figs. 1 and 2 the ends of the containers are beveled to conform to the external contour of the adjacent portions of the hull, being flush with the outer surface of the hull, and in practice each container is made of a series of annular, metallic sections bolted together at b, Fig. 4, to form water tight joints, steel tubing being the material preferably employed. Said containers are at such a distance below the water line of the vessel that they will be in solid water at all times, irrespective of pitching and rolling of the hull. A propeller is located in each container preferably amidships, the container being interrupted for the admission of the propeller, and as shown in Fig. 4 the propeller is of the screw type, having properly shaped and pitched blades C mounted on a hub C' which is secured to a shaft C² co-axial with the container B. Diametral struts b' within the container provide bearings for the

shaft C^2 , as shown in Fig. 4, and the propeller blades are peripherally connected with a ring C^x the inner diameter of which is the same as that of the container B , the exterior of the ring having sprocket or other teeth c^x thereon, for a purpose to be described. As shown in Fig. 4 this ring C^x is made of relatively large cross-section and revolves between abutting ends of the adjacent container-sections b^2 , which are made heavier than the other sections and are provided each with an external flange b^3 , the interrupted portion or annular opening of the container being located between the two sections b^2 . Between the flange and the side of the propeller ring C^x an annular bearing b^4 embraces the section b^2 and is secured thereon by bolts b^5 , said bearing being substantially L-shaped in cross-section, the radial portion thereof having its face adjacent the ring provided with alternate annular grooves b^6 and ribs b^7 to fit closely opposed ribs c^7 and grooves c^6 on the side of ring C^x , making a water-tight joint or connection therewith, and also serving as a bearing for the ring during its rotation. Setting-up bolts b^8 in the flange b^3 bear against the adjacent portion of the bearing b^4 and serve to set or adjust the same with the requisite tightness against the side of the propeller ring, the clamping bolts b^5 being tightened after the bearing is set up. In practice the bolt holes in bearing b^4 will be sufficiently elongated to allow of such adjustment.

From an inspection of Fig. 4 it will be seen that the propeller is supported axially mainly by the shaft C^2 and struts b' , and the bearings b^4 take up the end thrust, transmitted through the blades to said bearings, which also serve to maintain the container B water tight adjacent the propeller ring C^x .

Any suitable form of motor may be employed, such for instance as a turbine engine, indicated at E , Fig. 1, the shaft e having fixed to it a sprocket or other driving drum e' , connected with the peripheral ring C^x of the propeller by an endless flexible transmitting member e^2 , such as a sprocket chain, link belt, or the like.

In Fig. 3 the containers are shown side by side and driven from the turbines E located above them on the deck A^x , the containers being supported in suitable seats b^x , bolted to timbers A^2 at the bottom of the hold of the vessel. A very direct power transmission is thus provided between the motor and the propeller, and it will be obvious that the power transmitted is applied at the periphery of the propeller, adjacent the greatest resistance, rather than near the axis of rotation as is now common. By such peripheral application of the driving power I obtain greater efficiency from a motor of

given horse-power, with increased speed, and conversely, I can with a smaller expenditure of power secure a speed of propulsion equal to that attained by vessels using a much greater horse-power. As the propeller container is open at each end and thus in continuous communication with the main volume of water in which the vessel floats it will be apparent that the container is filled with a solid column of water under the pressure of the external water, the propeller operating in such solid body of water. There can be no lateral escape for the enveloping water and its discharge at the outlet end of the container is resisted by the pressure of the external water, hence there is practically no slip of the screw, and the axial distance traversed by the propeller (and the vessel) during one revolution of the propeller is substantially the theoretical distance for a given pitch and size of propeller, making proper allowance for friction. Thus the efficiency is increased by housing the propeller in the container, to revolve in a solid, confined body of water at all times, and in practice I have, with a given propeller and motor, arranged as herein provided, attained a speed of from four to six times as great as was attainable with the same dimensions and pitch of propeller, and power, used in the ordinary way.

Referring to Fig. 4 I have shown the container B provided with flanged seats B^5 located ahead and astern of the propeller, to receive gate valves B^6 , which can be moved to close the container B should it be necessary to get at the propeller in case of accident, or injury to the propeller, the closure of the gates serving to inclose the propeller in a water tight compartment, from which the water can be pumped by any suitable means, after which the thrust bearings can be removed to give access to the interior of the container. A nipple b^{10} on the container, normally closed by a cap b^{12} , Fig. 4, can be coupled onto a pump connection when it is desired to empty the part of the container between the closed gates or valves B^6 , which are shown fully closed in Fig. 4 to more clearly illustrate the construction. If it be desired to run the motor at a constant speed the speed of the vessel can be varied by closing the valves B^6 more or less.

By inclosing the propeller in the container so that it operates upon a solid body of water at all times I not only get the effect of immersing the propeller far below the surface but secure the added advantage of confining the water in which the propeller works from lateral displacement, as will be manifest.

Various changes or modifications in details of construction and arrangement may be made by those skilled in the art without

departing from the spirit and scope of my invention as set forth in the claims annexed hereto.

Having fully described my invention, 5 what I claim as new and desire to secure by Letters Patent is:—

1. The combination, with the hull of a vessel of a fore and aft tubular container extended longitudinally through the hull 10 and open at its ends, said container being interrupted within the hull, annular bearings mounted externally on the container at such interrupted portion, the opposed faces of the bearings having alternate annular ribs 15 and grooves thereon, a ring interposed between said bearings and having its opposite faces annularly ribbed and grooved to co-operate with the grooves and ribs, respectively, of the bearings, to form a water-tight 20 joint while permitting rotation of the ring, the latter closing the interrupted portion of the container between the bearings, a screw-propeller within said ring and having the peripheral portion of its blades rigidly attached to the ring, and means operatively connected with the exposed portion of the propeller ring to rotate the same.

2. The combination, with the hull of a vessel, of a fore and aft tubular container

extended longitudinally through the hull 30 and open at its ends, said container being interrupted within the hull, annular bearings mounted externally on the container and longitudinally adjustable thereon at such interrupted portion, the opposed faces 35 of the bearings having alternate annular ribs and grooves thereon, a screw-propeller having a rigidly attached ring inclosing the peripheries of its blades, said ring being interposed between the bearings and having 40 its opposite faces annularly ribbed and grooved to co-operate with the grooves and ribs, respectively, of the bearings, to form a water-tight joint while permitting rotation of the propeller and its attached ring, 45 axial supports for the propeller within the container, and means operatively connected with the exposed portion of the propeller ring to rotate the same, said ring closing the interrupted portion of the container 50 between the bearings.

In testimony whereof, I have signed my name to this specification, in the presence of two subscribing witnesses.

EUGENE A. GRAVES.
